JAW HOLDER

James H. Kindelberger, Pacific Palisades, Calif.,
assignor to North American Aviation, Inc.

Application March 7, 1949, Serial No. 80,056

9 Claims. (Cl. 153—48)

1

This invention pertains to a jaw-holding device for use in stretching and forming machines. Machines of the type illustrated in U. S. Patent No. 2,357,027, issued to R. Seifried for "Bending and Beveling Machine," are adapted to grip material, stretch the same to about its yield point, and form it about a curved die member.

Prior to this invention it has been necessary, when forming sheets of material, to use long sheets and cut off the wrinkled and warped portions resulting from the action of the ordinary gripping means. This has resulted in considerable spoilage and wastage of material.

Accordingly, it is an object of this invention to provide a jaw-holder so constructed that satisfactory forming may be obtained by a short grip on the material.

It is a further object of this invention to provide a jaw-holder so constructed that jaws carried thereby are arranged with respect to the material so as to prevent wrinkling and spoilage.

It is yet another object of this invention to provide a jaw-holder having a wide variety of jaw arrangements but requiring a minimum of adjustment.

It is still another object of this invention to provide a gripping arrangement which enables the use of sheets of material that are approximately the length of the finished sheet.

Further objects of invention will become apparent from the following description taken in connection with the accompanying drawings, in which:

Fig. 1 is a perspective view of the invention;

Fig. 2 is an elevational view of the jaw-holder;

Fig. 3 is a sectional view substantially along the line 3—3 of Fig. 2;

Fig. 4 is a view similar to Fig. 2 with parts in an extreme adjusted position;

Fig. 5 is an elevational view of a jaw adapted for use with the present invention; and

Fig. 6 is an elevational view of a modified jaw adapted for use with the present invention.

Referring now to the drawings, there is shown a jaw-holder 1 comprising a back-up plate 2 pivotally connected at 3 to a clevis 4 which in turn is adapted to be operatively connected to a cylinder (not shown, but which may be a part of the stretch forming machine illustrated in mentioned patent). Pivots attached to backup plate 2 are a pair of elongated jaw-holder plates 5, each of which has a plurality of slots 6 of suitable shape for slidably and rotatably receiving sheet-gripping jaw 7, such jaw per se being of conventional structure and having integral therewith a shank 8 and an enlarged portion 9 adapted to be slid-

ably received in slots 6. Nut 10 is adapted to be screwed into clamping position with the face of member 5 for holding the jaw in adjusted position.

Fig. 1 of the drawing shows the jaws gripping a sheet of material 11 in position to form it against die 12.

Referring now to Figs. 2 and 3, jaw-holder plates 5 are pivotally connected by bolt 13 and nut 14 to backup plate 2. The backup plate is provided with recesses 15 for adjustably receiving bolt 13, permitting the jaw-holder to be shifted laterally upon loosening of the nut 14 and pivoting of jaw-holder plates 5. This pivoting and sliding movement of plates 5 with respect to backup plate 2 is accomplished by screw thread 16 which actuates worm gears 17 pinned respectively to jaw-holder plates 5. Openings 18 are adapted to receive jaws 7' having relatively long shanks or pivot means 8' so that portion 9 thereof may fit in slots 6a contained in backup plate 2. This arrangement serves to hold the backup plate against separation from the jaw-holder plates.

In the operation of the device jaws 7 are predeterminedly positioned by pivotal movement of jaw-holder plates 5 with respect to backup plate 2 and sliding or rotating movement of jaws 7, the jaws being held in their preselected position by rotation of nut 10 into clamping position. Sheet material 11 is then attached to the jaws, stretched to about its yield point, and then wrapped or formed against die member 12.

In the arrangement illustrated in Fig. 4 the openings 18 are positioned adjacent the lower edge of plates 5 in order to provide a relatively wider range of adjustment of the jaws than is possible with the openings positioned as in Fig. 2. The pivot 18, as illustrated in Fig. 2, may be said to lie substantially on the longitudinal axis of the jaw holder plate, whereas in the arrangement illustrated in Fig. 4, the pivots may be said to be located eccentric to the longitudinal axis of such plate.

Although the invention has been described and illustrated in detail, it is to be clearly understood that the same is by way of illustration and example only and is not to be taken by way of limitation, the spirit and scope of this invention being limited only by the terms of the appended claims.

50 I claim:

1. A jaw holder for a stretching and forming machine of the type having jaws for gripping a sheet of material, stretching the same to about its yield point, and forming it about a curved die, said holder comprising a backup plate adapt-

ed to extend along an edge of said sheet, and a jaw holder plate pivoted on said backup plate to move laterally with respect thereto in a plane generally transverse to the plane of the sheet, jaws carried by said jaw holder plate and projecting toward said sheet, said jaws being rotatably and laterally adjustable with respect to said plate for preliminarily bending said sheet, and means for holding said jaws in adjusted position.

2. A device as recited in claim 1 in which said jaw holder plate is provided with a plurality of slots for laterally adjustably receiving said jaws.

3. A device as recited in claim 1 in which said jaw holder plate is provided with slots for slidably and rotatably receiving said jaws, said jaws being provided with a rounded shank and an enlarged portion for engagement in said slots.

4. A jaw holder for a stretching and forming machine of the type having jaws for gripping a sheet of material, stretching the same to about its yield point, and forming it about a curved die, said holder comprising a backup plate adapted to extend generally along an edge of said sheet, jaw holder plates pivoted on said backup plate to move generally transverse to the plane of the sheet, jaws adjustably carried by the jaw holder plate and projecting toward said sheet, and means connecting each of said jaw holder plates to said backup plate comprising pivot means and a pin and slot connection spaced from said pivot means for adjusting the positions of said holder plates with respect to said backup plate.

5. A device as recited in claim 4 in which each of said jaw holder plates is elongated along its longitudinal axis and said pivot means for each of said jaw holder plates lies substantially on said longitudinal axis.

6. A device as recited in claim 4 in which each of said jaw holder plates is elongated along its longitudinal axis and the pivot means of each of said jaw holder plates is located eccentric to said longitudinal axis.

7. A device as recited in claim 4 and further including means carried by said backup plate and engaging said holder plate for adjusting said jaw holder plates laterally and rotatably about said pin and slot connection and for holding them in adjusted position.

8. In a stretching and forming machine of the

type having jaws for gripping a sheet of material, stretching the same to about its yield point, and forming it about a curved die; a jaw holder adapted to extend in a direction generally along an edge of said sheet, a plurality of jaws carried by said holder and projecting toward said sheet, means on said holder for adjustably positioning said jaws laterally of said holder in a plane generally transverse to the plane of the sheet and into positions corresponding to the curve of the sheet when in its formed position and means for retaining said jaws in their adjusted positions on said holder during the stretching and forming operation.

9. In a stretching and forming machine of the type having jaws for gripping a sheet of material, stretching the same to about its yield point, and forming it about a curved die; a jaw holder, a plurality of jaws mounted on said holder and projecting toward said sheet, means on said holder for pivotally and laterally positioning said jaws with respect to said holder in a plane generally transverse to the plane of the sheet and to a position corresponding with the position of the portion of the sheet of material which it grips when in the formed position thereby to initially bend the sheet laterally prior to the stretching and forming operation, and means for holding said jaws in their adjusted position on said holder during the stretching and forming operation.

JAMES H. KINDELBERGER.
